UNITED STATES PATENT OFFICE

1,984,495

STORE FRONT CONSTRUCTION

Francis J. Plym, Niles, Mich., assignor to The Kawneer Company, Niles, Mich., a corporation of Michigan

Application July 24, 1933, Serial No. 681,835

6 Claims. (Cl. 20—56.4)

The present invention relates to store front constructions, and more in particular to a novel means and mechanism for adjusting and retaining the inner and outer sash retaining members 5 in their proper glass securing position.

Among the objects of the present invention is to provide a novel means and mechanism for properly positioning the inner and outer glass retaining sections.

- 10 A further object of the invention is to provide a novel bracket construction adapted to bridge the inner and outer glass retaining sections or members, as disclosed in the illustrated embodiment, and in the novel means to adjust the outer member or moulding in relation to the inner member and glass whereby to secure the glass in position with the proper and requisite amount of pressure, yet at the same time, not placing the pane of glass under any undue strain.
- 15 20 A further object of the invention is to provide a novel member adapted to be positioned intermediate the glass retaining members and formed with an elongated slot in which is slidably positioned a nut for receiving a screw or other threaded member. In the preferred embodiment, the bracket or member is pivotally positioned at its one edge, and as it pivots upon this edge, it changes its angular position as it is adjusted.

In the present embodiment of screw member 25 and nut, there is no binding on the threaded engagement between said screw and nut, by reason of the fact that the nut is shiftable in relation to the bracket and member and will automatically adjust its position for receiving the threads of the screw member as this screw is screwed down or unscrewed.

The invention further resides in the combination, construction, and arrangements of parts and details illustrated in the accompanying drawing, 30 and while there is shown therein a preferred embodiment, it is to be understood that the same is susceptible of modification and change, and comprehends other details, arrangements and constructions, without departing from the spirit of 35 the invention.

Further objects are to provide a construction of maximum simplicity, efficiency, economy and ease of assembly and operation, and such further objects, advantages and capabilities, as will later 40 more fully appear, and as are inherently possessed thereby.

Referring to the drawing:

Fig. 1 is a fragmentary view in front elevation of a store front or window utilizing the novel 45 sash construction;

Fig. 2 is a view in vertical cross section, taken on the line 2—2 of Fig. 1;

Fig. 3 is a cross sectional view taken in a plane represented by the line 3—3 of Fig. 2;

Fig. 4 is an enlarged vertical cross sectional view through the construction, and disclosing more clearly the novel adjusting means and nut.

Fig. 5 is a view in perspective of the bracket member.

Referring more particularly to the disclosure 10 in the drawing, the embodiment selected to illustrate the invention and utilizing the novel construction of sash is shown in a store front or window 1 adapted to form a setting for a pane 15 of glass 2. The sash is shown as mounted upon a sill 3 having a sheathing or covering 4, and against a riser 5 to which the inner sash member is suitably connected.

The sash construction comprises an outer sash member or moulding 6, and an inner sash member or pane seating section 7, adapted to receive and retain a pane of glass therebetween with an amount of pressure sufficient to retain it firmly in place, yet not enough to place the pane of glass under any undue strain. The outer sash member or moulding is provided at its lower edge with an inturned flange or lip 8 adapted to seat upon the sheathing or covering 4. Adjacent its upper edge, this outer sash member or moulding is provided with a glass abutting or contacting portion 9 adapted to bear against the pane of glass.

The inner sash member or pane seating section 7 is provided with a base portion 10 seating against the sheathing or covering 4, and provided with a raised portion for receiving the lip or flange 8 of the outer sash member or moulding. At its upper edge, the glass retaining member or inner sash member is provided with a longitudinally extending rib 11 forming a glass contacting or abutting portion, and also forming one side of a gutter or channel adapted to receive any condensate which might collect on and from the glass. The member 7 is bent to provide a ledge or rib 12 for receiving an edge of an intermediate member or bracket 13. As more clearly disclosed in Figs. 2 and 4, in the preferred embodiment of the present construction, the edge 14 of this bracket member seats intermediate the ledge or rib 12, and the base 10, while the opposite free edge 15 of this bracket member abuts against the glass contacting or retaining portion 9 of the outer sash member or moulding, and is adapted to draw this portion against the pane of glass, or to release it therefrom.

The bracket member 13 is provided with an elongated slot 16 in which is mounted a nut 17. The slot is considerably longer than the diameter of the nut, and the nut is thus slideable in this slot although prevented from being removed by reason of lips or projections 18 and 19 formed on the upper and lower sides, respectively. This nut is adapted to receive a screw or other threaded adjusting member 20 passing through an opening 21 in the gutter of the inner sash member or glass seating section 7. In order to add strength and rigidity to the bracket member, the same is shown as embossed at 22.

In the disclosed embodiment, the pane of glass is placed upon setting blocks and against the glass retaining portion 11 of the inner sash member which is shown as affixed to the riser and sill. This inner sash member carries a series of brackets 13 each provided with an adjusting nut 17 adapted to receive a screw 20 mounted in an opening in the gutter of the inner sash member. The outer sash member or moulding is then placed or slid in position with the upper edge 15 of the bracket seating against the glass abutting portion 9 of the moulding. As the screw 20 is tightened, it will withdraw the nut 17, and the latter will carry therewith the bracket 13 which in turn carries the outer sash member or moulding. Since the lower edge or rib 14 is positioned beneath the rib or ledge 12 of the inner sash member, the entire bracket is not free to move but must pivot upon this lower edge 14. Due to such pivoting, the bracket adjacent the nut will change its angular position, and as the screw member is in threaded engagement with the nut, in order to prevent binding of the threads of these complementary members, it is desirable that the nut be free to shift its position, and which it is free to do because of the elongated slot 16 in which it is slideable.

From the above disclosure and the description in the drawing, it will be readily apparent that the invention comprehends a novel means and mechanism for readily adjusting the sash member or the outer sash member relative to the inner one. By reason of the free movement of the nut in this bracket, the screw may be easily and readily tightened or unscrewed without the danger of undue binding of the parts or stripping 50 of their threads.

Having thus disclosed the invention,

I claim:

1. In a store front construction, the combination of an inner and an outer glass retaining member, a bracket connecting said members and pivot-

ally mounted on one of said members, an adjusting screw on the other of said members, and a nut carried by said bracket for receiving said screw, said nut being shiftable laterally of said members.

2. In a store front construction, the combination of an inner and an outer glass retaining member, a bracket associated with said members and pivoted at its lower edge on one of them, an adjusting screw on the other of said members, and a nut mounted on said bracket and shiftable relative thereto for receiving said screw and drawing said members into glass retaining engagement.

3. In a store front construction, the combination of an inner and an outer glass retaining member, a bracket bridging said members and positioned for tilting movement about an edge thereof, a screw in one of said members and a nut in said bracket for receiving said screw, said nut being adapted to move transversely of the bracket upon turning of the screw for tilting said bracket and drawing said members into glass retaining position.

4. In a store front construction, the combination of an inner and an outer glass retaining member, an element bridging said members and mounted for tilting movement about its lower edge, a screw in one of said members and a nut in said element for receiving said screw, said nut being adjustable laterally of said element so as to remain in operative alignment with the screw as the latter is being turned.

5. In a store front construction, a member mounted upon a sill and a member adjustable relative thereto, and means for positioning said members into glass retaining relation, said means comprising a bracket pivotally positioned on one of said members and adapted to carry the other, a nut in said bracket and adapted to be shifted transversely thereof, and a screw member adapted to be received in said nut and withdraw said bracket and the member carried thereby into glass retaining position, said nut shifting its position as said screw is turned whereby to remain in alignment with the screw.

6. In a store front construction, a member mounted upon a sill and a member adjustable relative thereto, and means for positioning said members into glass retaining relation, said means comprising a bracket pivotally positioned on one of said members and adapted to carry the other, a slot in said bracket, a nut shiftable in said slot, and a screw member adapted to be received in said nut and cause said nut to be shifted as said screw is turned and the bracket is pivoted.
